INVENTOR.
PHEBE T. PRIEST-
by Atty. N. DusBois,

UNITED STATES PATENT OFFICE.

PHEBE T. PRIEST, OF SPRINGFIELD, ILLINOIS.

DESIGN FOR A VESSEL-COVER.

SPECIFICATION forming part of Design No. 28,406, dated March 22, 1898.

Application filed November 19, 1897. Serial No. 659,204. Term of patent 7 years.

To all whom it may concern:

Be it known that I, PHEBE T. PRIEST, a citizen of the United States, residing at Springfield, in the county of Sangamon and State 5 of Illinois, have invented and produced a new and original Design for Vessel-Covers, of which the following is a specification, reference being had to the accompanying drawings, forming part hereof.

10 Figure 1 is a top plan view of a vessel-cover embodying my new design. Fig. 2 is a side elevation of same, and Fig. 3 is a vertical transverse section.

15 My design is applicable to vessels of that class in which the operation of boiling is commonly conducted—such as tea-kettles, coffee-pots, washboilers, and the like.

20 The leading or material feature of my device consists in the peculiar conformation of the vessel-top, whereby said top is provided with a radially-projecting extension of substantially the configuration shown.

25 My design in its minor details also involves the ornamental configuration of the vessel-cover, as hereinafter set forth.

The body A of the vessel-cover is approximately dome-shaped and its peripheral contour form is circular, as shown.

The design resides in a cover having the

particular shape and ornamentation disclosed 30 in the drawings. At the lower termination of the dome-shaped part of the cover is an annular flange a. A circular rim a' projects downward from the flange a. At the center of the top of the dome-shaped part of the 35 cover is an acorn-shaped knob b. A circular rib a², concentric with the knob b, surrounds the knob. A bent radial extension D starts from the dome-shaped part of the cover between the rib a² and the flange a' and 40 extends radially outward beyond the flange a, substantially as shown.

Foliated ornamentation a³ extends around the lower part of the dome-shaped part of the 45 cover.

Having described my invention, what I claim as new, and desire to secure by Letters Patent, is—

A design for a vessel-cover as herein shown and described.

In witness whereof I have hereunto subscribed my name, at Springfield, Illinois, this 50 15th day of November, A. D. 1897.

PHEBE T. PRIEST.
